UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

MOLD-SUPPORT.

1,229,678.

Specification of Letters Patent. Patented June 12, 1917.

Application filed December 20, 1916. Serial No. 137,980.

To all whom it may concern:

Be it known that I, HENRY TSCHERNING, a citizen of the United States, and resident of Freeport, in the county of Stephenson 5 and State of Illinois, have invented certain new and useful Improvements in Mold-Supports, of which the following is a specification, reference being had therein to the accompanying drawing.

10 In rock-over sand molding machines it is common to provide for the inverted flask a device which is readily adjustable to make contact at widely separated points with the lower flask-surface whether or not the latter is plane, and also to provide for vertical adjustment of the contact making devices to support equally well flasks of different vertical dimensions.

20 This invention pertains to novel devices of this general kind, wherein old ends are secured by improved means, and it also involves certain new results secured by new means.

In the accompanying drawings:

25 Figure 1 is a vertical section of the supporting devices on the line 1—1, Fig. 2.

Fig. 2 is a side elevation of the upper portion of the same devices looking from the left of Fig. 1, parts being broken away.

30 Fig. 3 is a plan view of the upper part of the structure seen in Figs. 1 and 2.

In these figures, 10 represents a suitable base, 11 a fluid pressure cylinder borne thereby, 12 a hollow plunger working in 35 said cylinder, 13 a smaller hollow plunger working in the larger one and rigidly fixed to, and upwardly closed by the central portion of, a frame 14 recessed to receive a superposed rocking H-like frame 15 having 40 at the ends of its central portion rounded downwardly projecting flanges the end faces 16 of which are slidingly supported, respectively, by downwardly converging hardened plates 17 fixed in the recessed portion of

45 the frame 14, the plates thus supporting the frame in such manner that pressure applied to one end only thereof causes it to tilt, the rounded end sliding on the plates 17. Each transverse end portion of the frame 15 is

50 provided with a longitudinal recess 18 having downwardly converging plates 19 upon which rest and readily slide the rounded ends 20 of tilting bars 21 each adapted to bear, near its ends only, upon a superposed 55 flask. Each bar, like the frame 15, tilts

when pressed down at one end only, its end faces sliding on the plates 19. Upon the top of the outer plunger 12 rests a spring 22 coiled about the smaller plunger, and upon the upper end of the spring rests 60 a collar 23 which is at will clamped to the smaller plunger, and the latter, although usually free to slide therein, is at will fixed in the larger or outer plunger by a set screw 24. When a flask is rocked over to position 65 above these devices, a small amount of compressed fluid is admitted to the cylinder by the tube 25 so as to hold it partly raised and then fluid is admitted, by the pipe 26, for example, to the inner plunger, and the 70 upper devices are thus raised until the bars 21 press and are adjusted against the lower surface of the flask. The collar is then forced down so as to give desirable compression of the spring and is then locked 75 to the inner plunger, and neither spring nor inner plunger require further adjustment until flasks of another size are to be used. If now the flask is freed from the rock-over devices its entire weight is supported by 80 the spring, the tension of which should be such that the full weight of the flask gives only slight additional compression. Compressed fluid being now allowed to escape from the cylinder by means of a pipe 27, 85 or other suitable devices, the spring compensates the loss of weight due to the flask's leaving the pattern, and the initial drawing movement is very gentle, even with rapid work. When, after drawing the pattern, the flask is lifted from these devices the spring would tend to lift suddenly the inner plunger and parts above, and this tendency may be neutralized by a quarter 90 turn of the set screws before the flask is 95 lifted, thus locking this plunger until it supports another flask, when it may be again unlocked.

I claim:

1. In apparatus of the class described, the 100 combination with a flask sustaining device including a body portion and tilting bars mounted thereon to receive directly a flask to be supported, of a vertically adjustable support for said device, and a spring interposed between the two and normally carrying the weight of said device and its load.

2. In apparatus of the class described, the 105 combination with a flask sustaining device including a body portion, a member mount-

ed thereon to rock in a vertical plane and independent bars transverse to said plane each having its ends only slidingly supported by said member, of a pneumatic cylinder having the piston arranged for raising and lowering said device.

3. In devices of the class described, the combination with a vertically adjustable 10 suitably recessed approximately horizontal frame, of a tilting member slidingly supported at its ends in the recessed frame, and adapted to tilt when downward pressure is applied at one end only of the member.

4. In devices of the class described, the 15 combination with a frame provided with parallel recesses each having at its ends downwardly converging smooth surfaces, of independent bars located in said recesses, respectively, and each having rounded ends 20 supported by and in sliding contact with the corresponding surfaces, whereby the bars may tilt independently to fit against the face of a superposed flask.

5. In a device of the class described, the 25 combination with means for raising a suitable frame, of an approximately horizontal frame spring-supported upon said means, arranged to tilt therein in a fixed plane, and provided with pairs of downwardly converging smooth face portions in position to support, respectively, the rounded ends of 30 flask-carrying bars, and flask-carrying bars each having its rounded ends slidingly supported by a pair of said face portions.

35 6. In apparatus of the class described, the

combination with a rigid frame having a set of suitable approximately parallel recesses with downwardly converging end faces, a tilting device impinging upon and supported by said faces and provided with 40 transverse recesses having analogous end faces, and flask-supporting rocking members impinging upon and supported by the last mentioned end faces, whereby a flask whether or not its lower face is plane may 45 receive proper support.

7. The combination with independent parallel bars adapted to support by their 45 end portions, only, an inverted flask and each having suitable end bearing-surfaces, 50 of a member having downwardly converging faces in position to support said bearing surfaces, respectively, means supporting said member and permitting it to rock in a plane transverse to said bars, and devices 55 for raising and lowering said means.

8. The combination with a fluid cylinder and plunger rod for lowering an inverted mold to separate it from the pattern, of a 60 rigid frame sustained by the plunger rod and provided with suitable ways having inclined end surfaces, bar-like mold sustaining devices having their ends resting against 65 said surfaces, respectively, and free to move thereon, and secondary analogous mold supporting devices similarly supported upon the devices first mentioned.

In testimony whereof I hereunto affix my signature.

HENRY TSCHERNING.
